UNITED STATES PATENT OFFICE.

DAVID P. TRUMP AND BURNARD M. GRIMES, OF HOLCOMB, WEST VIRGINIA; SAID TRUMP ASSIGNOR TO SAID GRIMES.

SASH-HOLDER.

No. 814,892.

Specification of Letters Patent.

Patented March 13, 1906.

Application filed November 29, 1905. Serial No. 289,599.

To all whom it may concern:

Be it known that we, DAVID P. TRUMP and BURNARD M. GRIMES, citizens of the United States, residing at Holcomb, in the county of Nicholas and State of West Virginia, have invented certain new and useful Improvements in Sash-Holders; and we do declare the following to be a full, clear, and exact description of the invention, such as will enable others skilled in the art to which it appertains to make and use the same.

Our invention relates to improvements in sash-holders; and it consists in the novel construction, combination, and arrangement of devices hereinafter described and claimed.

The object of the invention is to provide a simple, durable, inexpensive, and efficient device of this character which may be readily applied to a window-sash and which will effectively hold the same at any desired elevation and also prevent the same from being raised when in its closed position.

The above and other objects which will appear as the nature of the invention is better understood are accomplished by the construction illustrated in the accompanying drawings, in which—

Figure 1 is a detail view of a portion of a window sash and frame, showing the application of our improved holding and locking device. Fig. 2 is a vertical sectional view through the same. Fig. 3 is a horizontal sectional view. Fig. 4 is a perspective view of the device removed from the window-sash. Fig. 5 is a perspective view of the locking or clutch roller, and Fig. 6 is a perspective view of the operating piece or slide for the roller.

Referring to the drawings by numeral, 1 denotes a portion of a window-frame, 2 a sliding sash mounted therein, and 3 our improved holding and locking device. The latter comprises a body or casing 4, which, as shown, is of rectangular form and is preferably secured upon one of the side bars of the sash 2, so that it coacts with the usual strip upon the side of the frame 1. The body or casing 4, as here shown, is secured to the sash by screws passed through openings 5, formed in the flanged ends 6 of said casing. In the inner face of the body or casing 4 is formed a longitudinally-extending channel 7, which has its deepest portion at the center of the casing, and its inner or bottom wall is in-

clined outwardly in opposite directions, as shown at 8 9. This channel 7 opens upon the inner face of the body or casing 4, except at its central portion, which is closed by a cross bar or portion 10, as shown. In the side walls 11, formed by the channel 7, are provided angularly-extending slots 12, which are adapted to receive an operating piece or slide 13, which carries a locking or clutch roller 14. The latter is adapted to travel in the channel 7 and to be moved into and out of the same, and hence into and out of contact with the frame 1 by reason of its engagement with the inclined faces or surfaces 8 9 of said channel. The roller 14 is, as shown, of cylindrical form and is loosely mounted in the slide 13. The latter is in the form of a rectangular yoke, which slides in the slots or openings 12 and which has upon one of its sides a projecting knob or finger-piece 15, by means of which the slide, and hence the roller, may be shifted in the channel 7 to cause the roller to hold or lock the sash at any desired point. The enlarged collar 16, which is formed at the inner end of said knob and which engages the outer face of the body or casing 4, coacts with a spring 17, which is mounted upon said face of the casing, as clearly shown in Fig. 4 of the drawings. This spring has oppositely-inclined end portions 18 and a central depressed portion 19, which forms a seat for the collar 16 of the knob 15 and is adapted to hold the slide and the roller 14 in the central portion of the channel 7 beneath the cross-bar 10, so that the window-sash may be readily elevated or lowered when the parts are in this position. It will be seen that when the knob 15 is moved upwardly the roller 14 will be shifted into engagement with the inclined surface 8, and as it rolls upwardly upon the same it will be forced outwardly into engagement with the frame 1 or the usual strip upon the latter, and the sash will be supported at any desired elevated position. When the sash is in its closed position and the knob 15 is shifted downwardly to cause the roller to engage the inclined surface 9 of the channel 7, the roller will be wedged outwardly and will prevent the opening of the sash, as will be readily understood.

From the foregoing description, taken in connection with the accompanying drawings, the construction, operation, and advantages

of the invention will be readily understood without requiring a more extended explanation.

Having thus described our invention, what we claim as new, and desire to secure by Letters Patent, is—

1. A device of the character described comprising a casing having a channel therein formed with an inclined surface and with guides, an operating - piece slidable in said guide, an antifriction device in said operating-piece adapted to coact with the inclined surface in said casing, and a spring for holding said operating-piece against movement.
- 15 2. A casing for attachment to a window-sash and having a longitudinal channel in one

side, the bottom of which channel is inclined and the side walls of which are provided with inclined slots converging toward one end of the casing, in combination with a yoke slideable in said slots, extending across the channel and having an opening between the side walls thereof, and a roller in said channel and extending through the opening in the yoke.

In testimony whereof we have hereunto ²⁰ set our hands in presence of two subscribing witnesses.

DAVID P. TRUMP.
BURNARD M. GRIMES.
